DESIGN FOR A CASING FOR AN ELECTRIC SHAVER

George T. Scharfenberg, Chicago, Ill., assignor to
Chicago Flexible Shaft Company, Chicago, Ill.,
a corporation of Illinois

Application March 24, 1938, Serial No. 76,079

Term of patent 14 years

To all whom it may concern:

Be it known that I, George T. Scharfenberg, a citizen of the United States, residing at Chicago, in the county of Cook and State of Illinois, have invented a new, original, and ornamental Design for a Casing for an Electric Shaver, of which the following is a specification, reference being had to the accompanying drawing, forming part thereof.

In the drawing:

Figure 1 is a perspective view of a casing for an electric shaver showing my new design;

Figs. 2 and 3 are side views of the casing taken at 90°, one with respect to the other; and

Fig. 4 is a top plan view thereof.

I claim:

The ornamental design for a casing for an electric shaver, substantially as shown.

GEORGE T. SCHARFENBERG.
